UNITED STATES PATENT OFFICE.

HOWARD W. SMITH, OF ELLWOOD CITY, PENNSYLVANIA.

PIPE-THREADING DIE.

Application filed May 28, 1923. Serial No. 641,987.

My invention relates to dies for threading pipe and for similar purposes, and its object is to provide an improved threading die which shall be capable of cutting long, 5 tapered threads with the use of relatively short chasers.

In cutting tapered pipe threads it is necessary that the chasers in the die be at least as long, with a little to spare, as the thread 10 that is to be cut. For very long threads it has heretofore been necessary to employ correspondingly long chasers, and the hardening of such chasers is a difficult matter on account of the fact that they tend to change 15 their shape. One harmful result of this, among others, is that the pitch of the thread in such a chaser is not accurate.

According to my present invention I provide pipe-threading dies adapted for cutting long, tapered threads without the use of unusually long chasers, and in a manner which will allow any inequalities in the thread to be easily corrected. I accomplish 20 this result by providing a ring which supports the chasers in grooves which are so arranged that short chasers may be inserted therein and will be held rigidly in the proper position to cut threads that are longer than the length of any one of the chasers.

30 In one arrangement for this purpose, I provide the supporting ring with a central groove and with grooves for receiving the chasers extending laterally from the central groove and staggered so that the sides of the grooves form seats for the ends of the chasers. In another construction for the same general purpose, I split the supporting ring centrally and provide grooves for the chasers which extend across the ring sections. 35 In this construction, the chasers are preferably staggered as in the arrangement where a central groove is provided in the supporting ring. If desired, however, the split ring sections may be so arranged that the chaser grooves are in line with each other, in which case the short chasers are arranged end to end with their inner ends in contact.

Another feature of my invention consists 50 in providing fewer chasers on the back row than in the front row. The chasers do their heaviest work at the front of the die where the cut begins, and the work of cutting the rear portions of the threads may be done with only half as many chasers as are necessary in cutting the front portions of the

threads. This arrangement is intended to be used only for the larger sizes of pipe and not for smaller sizes where the total number of chasers in an ordinary die is six or 60 less.

In the accompanying drawing, Fig. 1 is a side elevational view of a ring die supported in an expanding shell and provided with chasers arranged according to my present 65 invention; Fig. 2 is a vertical sectional view taken through the construction of Fig. 1 and substantially on the line 2—2, Fig. 1; Fig. 3 is a vertical sectional view taken through a modified construction, and Fig. 4 is a vertical 70 sectional view showing another modified construction.

In Fig. 1 of the drawing the numerals 2 and 3 indicate the upper and lower semi-circular halves of an expanding shell which are pivoted at one end upon pivot-bolts 4 connected by links 5. The expanding shell is opened and closed on side opposite the pivot-bolts 4 by means of a vertical screw 6 having right and left threads extending 75 through screw-thread openings which are formed in round pins 7 that are received in horizontal openings in projections 8 at the ends of the sections 2 and 3. This arrangement permits the screw 6 to engage the pins 80 or round nuts 7, without binding, in all angular positions of the die sections, the two halves of the expanding shell being free 85 to rotate around the pins 7 whenever the dies are opened or closed. A handle 9 is secured to the upper end of the screw 6, and an auxiliary screw 10 and a nut 11 may be provided for fixing the adjusted position of the expanding shell.

Within the expanding shell is a removable 90 ring die consisting of two sections 12 each of which fits into its half of the expanding shell and is removably secured therein by means of a guide pin 13 and a bolt 14. The guide pin 13, as shown in Fig. 1, is driven 95 from the inside in a hole in the expanding shell and is riveted on the outside. The ring dies are thus readily removable.

As shown in Fig. 2, the ring-die sections are provided with central grooves 15 and 100 with countersunk grooves 16 at their edges, the latter grooves being arranged to receive clamping rings 17 which are secured to the ring sections 12 by means of screw-bolts 18.

Chasers 19 are held in radial grooves 110 which extend from the central grooves 15 to the outer edges of the ring sections. As

shown in Fig. 2 the chasers 19 are staggered so that each chaser may extend across the groove 15 and rest against the opposite side of this groove. The clamping plates 17 5 clamp the chasers 19 rigidly in position. It will thus be seen that effective cutting edges are provided across the entire distance between the clamping plates 17, and this result is accomplished by comparatively short 10 chasers. It will also be seen that any inequalities in the thread which may be produced with an imperfect chaser may be readily corrected by replacing the particular chaser section which is at fault.

15 In the construction shown in Fig. 3, the ring-die sections are split centrally instead of being formed with central grooves. The upper and lower sections of the ring-die are indicated at 20 and 21, respectively, and 20 are split on the line 22, the separate portions of the ring-die members being connected together by means of bolts 23.

Chip-grooves 24 are formed in the combined ring-die sections and short chasers 25 25 are received in slots that are formed in the chip-grooves 24. The chasers 25 shown in Fig. 3 are somewhat shorter than the width of the ring-die sections and are held in position by means of set-screws 26^a which extend through threaded openings in the clamping rings 26. Two pairs of the set-screws 26^a are shown in Fig. 3, the remaining set-screws being omitted for the sake 30 of clearness.

35 It will be observed that the die shown in Fig. 3 has one half as many chasers on the left or back row as on the right or front row. As stated above, the chasers do their heaviest work at the front end where the 40 cut begins and fewer chasers in the back row are sufficient. The clamping rings 26 are clamped in position by means of screws 27.

The modified construction shown in Fig. 45 4 differs from that shown in Fig. 3 in that the chaser sections are arranged end to end instead of being staggered, and are equal in number on both sides of the ring-die. The upper and lower sections of the ring-die are indicated at 30 and 31, respectively and are 50 both split on the line 32, the separate portions of the ring-die members being connected together by means of bolts 33.

Short chasers 34 are received in grooves 55 formed end to end in the ring-die sections, and are clamped in place by means of clamping rings 36 and bolts 37 similar to the corresponding parts shown in Figs. 1 to 3.

In assembling this form of my device, the clamping rings 36 are first secured to the 60 separate portions of the ring-die sections, the chasers are placed in their grooves, and the separate portions of the die-sections are secured together by means of the bolts 33, after which the clamping rings 36 are tightened by means of the screw-bolts 37 to rigidly clamp the chasers.

65 My invention is not restricted to the use of two rows of chasers since the dies may be readily built with the total length of the 70 chasers divided into three or more sections instead of two.

75 It will also be understood that my invention is not restricted to the other details of construction herein shown, since these may be modified in any desired manner within the scope of the appended claims.

I claim as my invention:

1. A threading die comprising a circularly curved holder having an internal groove formed parallel to the sides thereof, and chasers shorter than the width of said holder, said chasers being disposed in transverse grooves which extend from the sides of said holder to the said central groove and which are staggered with respect to each other.

80 2. A threading die comprising a circularly curved holder having an internal central groove formed parallel to the sides thereof, and chasers shorter than the width of said holder, said chasers being disposed in transverse grooves which extend from the sides of said holder to the said central groove and which are staggered with respect to each other, and side members for clamping the 85 said chasers against the opposite walls of said central groove.

90 3. A threading die comprising a shell split diametrically to form semi-circular sections which are pivotally adjustable, semi-circular ring sections removably secured within 95 said shell sections, each of said ring sections having an internal central groove and having lateral grooves extending between said central groove and the sides of said ring sections, chasers disposed in said lateral grooves, each of said chasers extending between the open end of its groove and the 100 opposite wall of said central groove, and clamping members secured to the sides of 105 said ring sections.

110 In testimony whereof I, the said HOWARD W. SMITH, have hereunto set my hand.

HOWARD W. SMITH.
